[57] CLAIM

The ornamental design for a charger unit for battery
powered diagnostic instruments, as shown and de-
scribed.

DESCRIPTION

FIG. 1 is a front elevation of a charger unit for battery
powered diagnostic instruments embodying my new
design;

FIG. 2 is a rear elevation thereof;

FIG. 3 is a right side elevation thereof; the left side
elevation being a mirror image of the right side eleva-
tion;

FIG. 4 is a top plan view thereof; and

FIG. 5 is a bottom plan view thereof.

The broken lines are shown for illustrative purposes
only.FIG. 2
